2 SHEETS—SHEET 2.

UNITED STATES PATENT OFFICE.

HENRY W. WILLIS, OF LANSFORD, NORTH DAKOTA.

GRAIN-CAR DOOR.

1,249,703.

Specification of Letters Patent. Patented Dec. 11, 1917.

Application filed March 28, 1914. Serial No. 827,893.

To all whom it may concern:

Be it known that I, HENRY W. WILLIS, citizen of the United States, residing at Lansford, in the county of Bottineau and State of North Dakota, have invented certain new and useful Improvements in Grain-Car Doors, of which the following is a specification.

My invention relates to new and useful improvements in grain car doors, the object of my invention being to provide an improved grain car door of the type employing co-acting upper and lower door sections, each mounted for independent movement for opening.

A further object of my invention is to so construct the door sections that in open position they may be swung to lie fully out of the way.

20 A yet further object of my invention is the provision of means for fastening the doors when closed in such a manner that all leakage of grain or other contents of the car is prevented.

25 With these and other objects in view, my invention will be more fully described, illustrated in the accompanying drawings, and then specifically pointed out in the claim which is attached to and forms a part of this 30 application.

In the drawings:—

Figure 1 is a front elevation of a preferred form of grain car door construction;

Fig. 2 is a transverse sectional view taken 35 on the line 9—9 of Fig. 1;

Fig. 3 is a vertical sectional view taken on the line 10—10 of Fig. 1, the open position of the upper door being shown in dotted lines.

40 Corresponding and like parts are referred to in the following description and indicated in all the views of the drawings by the same reference characters.

In order to insure a clear understanding of 45 the construction and operation of my improved grain car door, I have illustrated the same in connection with a grain car 10 having a door opening defined by spaced door posts 71, a threshold and a lintel each 50 designated 82. My improved form of grain car door construction includes upper and lower doors 64 and 65, respectively, the upper door being constructed to swing inwardly to rest against the roof of the car 55 when in open position, while the lower door is adapted to swing outwardly to hang

against the forward face of the sill. Each of these doors is preferably formed from a single piece of sheet metal corrugated transversely as clearly shown in Fig. 3 of the 60 drawings and each door is provided adjacent its ends with vertically extending brace strips or bars 66 of metal, bolted, riveted or otherwise secured to the sheet metal forming the doors. 65

Extending along the outer faces of the doors, preferably intermediate their height, are truss rods 67 which are tightened and held in position, with their intermediate portions bowed outwardly, by means of braces 70 68. Each brace is formed from a single bar of metal bent substantially U-shaped with its terminals directed away from each other and bolted or riveted to the door as shown at 69 and with its bight portion rebent centrally to 75 form a seat 70 for the intermediate portion of the truss rod to space the same away from the door. The door posts 71, adjacent their lower ends, are provided with vertically disposed stops 72 formed from strips of iron 80 bolted to the posts and arranged to limit inward swinging movement of the lower door, while the door posts above the stops 72 are provided with similar stops 73 arranged to limit outward swinging movement of the 85 upper door, the stops 72 and 73 being so arranged with respect to each other that the door sections, in closed position, will be in vertical alinement with their adjacent edges 90 overlapping as clearly shown in Fig. 3. Because of the corrugating of the sheet metal forming the doors, this overlapping joint is extremely tight and all leakage of grain from the car or moisture into the car is prevented. The stops 72 and 73 also prevent 95 leakage of grain past the side edges of the door sections.

In addition to the brace strips 66 I provide hinge plates 74 which also act as brace strips and the ends of which extend to the lower edge of the lower door and beyond the upper edge of the upper door and are bent to form hinge rod receiving eyes 75. The doors are swingingly mounted upon hinge rods 76 which are retained by these 100 eyes and the hinge rods are preferably additionally secured to the door by bending the adjacent edges of the sheet metal forming the doors about the intermediate portions of the hinge rods as shown at 77. Each 105 hinge rod is formed from a single metal rod having its end portions bent laterally 110

as shown at 78 with their terminals extended in opposite directions and parallel to their bodies as shown at 79, forming in effect crank hinges, the terminals of the hinge rod 5 of the upper door 64 being journaled in bearings 80 secured to the inner faces of the door posts 71, while the terminals of the hinge rod of the lower door 65 are extended into sockets 81 formed in the opposed 10 faces of the door posts 71 and adjacent the sill 82.

The outer edge of the door sill is channeled vertically as shown at 83 to receive the laterally directed curved portions 78 15 of the lower hinge rod when the lower door is swung outwardly to open position, thus permitting the door to hang beneath the car and in substantially the same plane with the front of the sill when the lower door is 20 opened. The laterally directed portions of the hinge rod for the upper door 64, are so proportioned that when the door is swung inwardly and upwardly to the position shown in dotted lines in Fig. 3, the door may 25 rest snugly against the roof of the car, being held in place by a swinging hook 84 carried by a hook plate 85 bolted to one of the transverse rafters 86 of the car, the bill of the hook engaging against the lower face of the 30 door when the latter is in raised position. To prevent disengagement of the hook, due to vibration of the car, I provide a locking pawl 87 pivoted to in one position engage 35 against the rear face of the shank of the hook, which face is provided with a stop shoulder 88 to prevent disengagement of the pawl from the hook through gravity.

In order to lock the lower door in closed position, I provide each door post with a 40 lock in the form of a plate 89 having a slot 90 through which a pin 91 passes, whereby the plate is slidably mounted upon the post. This slot, as shown, is disposed diagonally 45 of the plate so that sliding of the plate along the pin will cause its inner end to move outwardly away from the door. Stop pins 92 are provided to prevent swinging of the plate when forced to its innermost position, that is, into engagement with the outer face 50 of the lower door 65. The upper door 64 is secured against swinging movement, when in closed position, by means of button forming plates 93 swingingly mounted upon the outside of the door 64 adjacent its lower 55 edge and adapted, in one position, to extend by their free ends over the upper edge portion of the lower door.

From the foregoing description, the operation of the grain car door of the type

shown will be readily understood and no further description is therefore believed to be necessary. It should be noted, however, that in opening the lower door 65, the door may be first swung about the crank portion of its hinge rod as a pivot until it rests upon the crank arms of the rod when it may be further swung or tilted, together with the hinge rod about the pivoted terminals of the rod until the door depends in substantially a vertical plane with the crank arms 70 of the hinge rod extending upwardly and outwardly. The door may then be lowered by outward and downward swinging of the crank arms of the hinge rod while the crank portion of the rod turns in its bearings on 75 the door. It will therefore be clear that the lower door may be opened when the space between the car and warehouse is even a trifle less than the height of the lower door, and that when open, the lower door will be 80 entirely out of the way and not liable to injury should the car be moved.

Although I have illustrated and described my car door construction in detail, it will of course be understood that I do not wish to 85 limit myself to the specific details of construction shown, as various minor changes, within the scope of the appended claim, may be made at any time without in the slightest degree departing from the spirit of my invention.

Having thus described the invention, what is claimed as new is:

The combination with a grain car having a door opening including spaced posts and 95 a transverse sill, there being vertical recesses formed in the outer face of the sill and sockets formed in the inner faces of the door posts and spaced from the sill, of a door section forming a closure for the lower part 100 of the door opening, and a rod hingedly connected to the lower edge of the door section and provided with oppositely disposed crank arms, the terminals of which are journaled in the sockets, said door section being 105 movable to open position at the front of the car and below the sill with the crank arms seated in the vertical recesses in the sill and with the then outer face of the door section substantially in the plane of the outer face 110 of the sill.

In testimony whereof I affix my signature in presence of two witnesses.

HENRY W. WILLIS. [L. S.]
